Primary Examiner — Ian Simmons*Assistant Examiner* — Keith Frank(74) *Attorney, Agent, or Firm* — Keeley DeAngelo LLP;
W Scott Keeley(57) **CLAIM**

The ornamental design for a powder container, as shown and described.

DESCRIPTION

FIG. 1 is a front-perspective view in situ according to the present invention;

FIG. 2 is a front-perspective view according to the present invention;

FIG. 3 is a rear-perspective view according to the present invention;

FIG. 4 is an orthographic front-view according to the present invention;

FIG. 5 is an orthographic right-side view according to the present invention;

FIG. 6 is an orthographic rear view according to the present invention;

FIG. 7 is an orthographic left-side view according to the present invention;

FIG. 8 is an orthographic top view according to the present invention; and,

FIG. 9 is an orthographic bottom view according to the present invention.

The broken lines in the drawings showing of the powder container form no part of the claimed design.
